(57) **CLAIM**

The ornamental design for a shoelace baseball glove, as shown and described.

DESCRIPTION

FIG. 1 is a front perspective view of a shoelace baseball glove.

FIG. 2 is a rear perspective view of a shoelace baseball glove.

FIG. 3 is a top view of a shoelace baseball glove.

FIG. 4 is a bottom view of a shoelace baseball glove.

FIG. 5 is a left side view of a shoelace baseball glove; and,

FIG. 6 is a right side view of a shoelace baseball glove. The broken lines on the glove are understood to represent stitching.
